UNITED STATES PATENT OFFICE.

HENRY KENYON BURCH, OF MIAMI, ARIZONA.

APPARATUS FOR CLASSIFYING ORES.

1,267,373.

Specification of Letters Patent. Patented May 28, 1918.

Application filed November 8, 1916. Serial No. 130,341.

To all whom it may concern:

Be it known that I, HENRY KENYON BURCH, residing at Miami, in the county of Gila and State of Arizona, a citizen of the 5 United States, have invented or discovered certain new and useful Improvement in Apparatus for Classifying Ores, of which improvement the following is a specification.

The invention described herein relates to 10 certain improvements in an apparatus for crushing and classifying ores. Heretofore it has been the custom to feed the ore as it comes from the crushing mill to a ball mill for reduction to a condition permitting of 15 a concentration of the values and the separation of the latter from the gangue. One pass through the bar mill will not sufficiently reduce all the material when it is necessary for the extraction of the values to 20 finely comminute the ore. In such cases it is customary to discharge the mixed fine and coarse material into a classifier in which the fines and over sizes are separated, and then return the latter by an elevator or other 25 suitable means to the ball mill for further reduction.

The invention hereinafter described has for its object a combination of mills and classifiers wherein the ore is suitably fed 30 to each of the mills, and each of these mills feeds the oversize material to the other mill, through the classifiers, the latter being adapted to discharge such oversizes directly to the feed boxes of the respective mills.

35 The invention is hereinafter more fully described and claimed.

In the accompanying drawings forming a part of this specification, Figure 1 is a top plan of a crushing plant embodying my improvement; Fig. 2 is a similar plan showing a modification of the combination and Fig. 3 is a side elevation of the combination shown in Fig. 1.

In the practice of my invention, two pul- 40 verizers or comminuting machines, such as ball mills 1 and 2, are arranged opposite to each other and preferably with their feed ends inwardly, as shown in Fig. 1. The material to be crushed or comminuted is raised 45 by any suitable means to a tank or receiver 3, elevated to a suitable height, and from this tank or receiver, the material mixed with a suitable amount of water is directed by chutes 4 in substantially equal quantities 50 to the feeding troughs or boxes 5 of the respective mills. The material is removed by

scoops 6 from these boxes and delivered through hollow trunnions to the interior of the mills where the material is crushed and ground and discharged through the hollow 60 trunnion 7 into troughs or launders 8. By these launders the crushed material consisting of fines and over sizes and just as they come from the mill, are delivered to classifiers whereby the fines and oversizes are separated, 65 the one from the other. The classifiers are preferably of a type in which the fines will be discharged over spillways at the lower end of the classifier into launders 9, and the oversizes will be caused to move 70 upwardly and discharged either directly or indirectly into the feed boxes 5 of the respective mills, so that such oversizes may be subjected to further crushing or comminution. It is preferred to employ a type of 75 classifier known as the "Dorr" classifier, which consists of an inclined trough 11 and a series of combs 12 carried by reciprocated frames 13, said frames being adapted to be raised when moving downwardly toward the 80 lower end of the trough and to be lowered into such position so that the teeth of the combs will project into the materials in the troughs during their upward stroke. The teeth of these combs are so spaced as to 85 permit the passage between them of any material sufficiently comminuted but to draw upwardly all oversizes. At their lower ends these troughs are provided with a spillway 14, over which the water carrying the 90 fine material will flow into launders 9, which are arranged to discharge the fines in a box or receptacle 15 from which they are conducted away by a launder.

By reference to Fig. 1 it will be seen that 95 the classifier which receives material from the mill 1 and directs it into the feed box of the mill 2, is so arranged as to discharge the material into that end of the feed box from which the scoop 6 gathers the material. The 100 other classifier, however, would discharge material into the opposite end of the feed box of the mill 1, and in order that the material may be in position to be gathered by the scoop 6 of the mill 1, the over sizes are 105 discharged into a trough 16 in which is located a screw 17 adapted to move the material along the trough and to an opening into what is termed the feed-end of the feed box of the mill 1. In the form of a plant shown 110 in Fig. 1, the ball mills are arranged with their axes in, or approximately in aline-

2
ment the one with the other, but if desired, these mills may be arranged with the axes parallel, the one with the other, and provision made for the classifier to discharge 5 into troughs connecting with the feed boxes of the respective mills, and so inclined that the material discharged thereto, will flow down to position to be lifted by the scoops.

As hereinbefore stated, the material to be 10 crushed is fed into both mills simultaneously, and preferably in about equal quantities, and the material, after passing through the respective mills, goes to the classifiers where the fines are separated out 15 and the oversizes go to the other mill, where they will mingle with the new material being fed to such mills. An exact equality of feed is not necessary in my improved method for the reason that if the surplus of material 20 is fed to one mill, it will be discharged therefrom and pass by the way of the classifier to the other mill, which is capable of operating on the surplus material.

It is characteristic of my improvement that 25 the mills with their classifiers and connecting launders are arranged in parallel series and that after the material is fed to a mill

it enters what might be termed a closed circuit and moves therethrough until it has reached the desired grade of fineness when 30 the materials from both mills are brought together and conducted to a concentrating plant.

I claim herein as my invention:

1. In an ore crushing or comminuting 35 plant, the combination of two crushing mills, means for feeding ore to said mills, and means including classifiers for conducting material from the discharge opening of each mill and discharging coarse material 40 to the feed opening of the other mill.

2. In an ore crushing or comminuting plant, the combination of two crushing mills arranged in or approximately in the same horizontal plane, classifiers arranged 45 to receive material from the discharge openings of the respective mills and to raise the oversize material to such a height that it will flow to the feed boxes of the other mill.

In testimony whereof, I have hereunto set 50 my hand.

HENRY KENYON BURCH.

Witness:

BERTHA M. HUNT.
